A. WIRTHWEIN

PHOTOGRAPHIC PRINTING DEVICE

Filed Jan. 26, 1925

Patented Feb. 9, 1926.

1,572,699

UNITED STATES PATENT OFFICE.

ALBERT WIRTHWEIN, OF MILWAUKEE, WISCONSIN.

PHOTOGRAPHIC-PRINTING DEVICE.

Application filed January 26, 1925. Serial No. 4,951.

To all whom it may concern:

Be it known that I, ALBERT WIRTHWEIN, a citizen of the United States, residing at Milwaukee, county of Milwaukee, and State 5 of Wisconsin, have invented new and useful Improvements in Photographic-Printing Devices, of which the following is a specification.

This invention relates to improvements in 10 photographic printing devices.

It is the primary object of this invention to provide a novel and simple printing machine in which opportunity is afforded for manipulation of the light reaching different 15 portions of the negative during exposure and in which the printing operation is greatly facilitated through the incorporation of an improved mounting for the printing frame and improved means for disposing of the exposed prints prior to development.

More specifically stated, it is the object of this invention to provide an arrangement whereby the making of a number of prints 25 from a single negative will be expedited through an arrangement by which the adjustment of the machine for the purpose of introducing a new print will automatically take care of the exposed print, whereby it 30 may be stored in a darkened container, pending the completion of the batch of exposures.

In thus providing for the rapid substitution of sensitized sheets in the printing 35 frame it is my purpose also to provide for the manipulation of exposures of different portions of the negative and to incorporate novel and improved means for controlling printing and ruby lights at properly timed 40 intervals with respect to the operation of the frame.

In the drawings:

Figure 1 is a transverse vertical sectional view through a device embodying this invention.

Figure 2 is a horizontal section taken on the line indicated at 2-2 in Figure 1.

Figure 3 is a plan view of the device on a reduced scale.

Like parts are identified by the same reference characters throughout the several views.

The device includes a cabinet 10 which is adapted to rest upon a table or shelf 11.

Secured to the cabinet in a position to depend below the margin of the table 11 is

a storage box 12 having an inwardly opening cover 13 normally held in closed position by a spring hinge 14. An opening at 15 affords communication between the interior of the storage box 12 and the interior of cabinet 10.

Cabinet 10 is provided with an opening 20 in its front wall and includes a source of illumination which, for the purposes of the present invention, is represented as comprising a reflector 21 containing an incandescent electric bulb 22. Light emanating from bulb 22 and reflector 21 reaches the interior of the cabinet through opening 23 60 65 70 therein although, for the purposes of this invention, the reflector 21 may be regarded as constituting a part of the cabinet.

A printing frame designated in its entirety by reference character 25 is supported for rotation about a horizontal axis extending transversely of the cabinet. Suitable journal boxes 26 are mounted on the interior of the side walls of the cabinet and trunnions 27 connected with the printing 80 frame are operatively mounted in the journal boxes so that the printing frame may readily be swung between the positions represented in full and dotted lines in Figure 1. It will be noted, however, that the arc 85 through which the printing frame oscillates between such positions exceeds 180° so that the printing frame, which during the printing operation is disposed horizontally beneath reflector 21, may, upon occasion, be 90 95 swung about its trunnion support to an inverted and inclined position as shown in dotted lines.

The cabinet contains in its lower rear portion a so-called safe light or ruby light 29 95 for the purpose of facilitating the positioning of negatives and paper in the printing frame. For the operation of the bulb 29 and the printing bulb 22, suitable electrical connections are provided which, for the 100 purposes of present disclosure, are illustrated diagrammatically.

A supply cable 30 leads to the machine. One conductor 31 supplied by this cable conveys current to one of the terminals 105 above 22 and to the resilient switch plate 32, the latter being supplied by a branch conductor 33. A second conductor 34 connected with a wire in cable 30 has a branch 35 which goes to one terminal above 29 110 and another branch 36 which leads to the fixed terminal 37 of a switch controlling

operation above 22. A conductor 37 connects bulb 22 with a resilient switch member 38 adapted for contact with fixed terminal 37 and provided with a shoulder 39 against 5 which the switch actuating lug 40 on the printing frame abuts. The arrangement is such that the switch member 38 normally maintains itself resiliently out of contact with the fixed switch terminal 37. But as 10 the printing frame swings counterclockwise in a direction opposite to that indicated by the arrows in Figure 1, the lug 40 on the frame strikes the shank portion of spring contact 38 and ultimately forces the end of 15 such contact into engagement with the fixed contact 37 whereby to close the switch. Shoulder 39 limits the oscillatory movement of the frame in a counterclockwise direction. The obvious purpose of lug 40 is to render 20 the frame eccentric with reference to its fulcrum so that the opposite end of the frame will clear the spring contact 38 without closing the switch when the frame is being swung between its dotted and full line 25 positions.

The resilient switch member 32 is provided with an outwardly bowed portion 41 adapted to be contacted by the side margin 42 of the frame. As the frame reaches the 30 inverted position in which it is shown in dotted lines in Figure 1, through such contact the resilient spring member 32 is forced into engagement with the fixed contact member 44 whereby to close a circuit through 35 such member and through the conductor 45 which leads to the other terminal of bulb 29. Thus when the frame is in its horizontal position, as indicated in full lines in Figure 1, bulb 22 will be lighted and will 40 expose sensitized paper contained in frame 25. When the frame is inverted, however, the initial movement thereof opens the circuit to bulb 22 by allowing spring 38 to move slightly outwardly and ultimately 45 lights bulb 29 through the closing of the switch which comprises resilient contact 32 and fixed contact 44.

The printing frame 25 is provided in the 50 usual manner with a glass or transparent sheet of material at 47 and may have a mask at 48 adapted to receive a negative which is shown in black at 49. The usual pressure back 50 may conveniently be made of hingedly related component parts 51 and 52, 55 the latter being hinged to the printing frame at 53. A slot 55 in the rail of the frame to which the pressure back is hinged communicates with the space between the pressure back and the mask. Therefore, a 60 sensitized sheet 60 confined within said space may readily find egress through slot 55 when the frame is tilted to its dotted line position.

A flexible cord or the like at 61 passes 65 through opening 15 and connects door

13 with the end of frame 25 opposite to that in which the slot 55 is located. The arrangement is such that as the frame 25 oscillates toward its ultimate position, as shown in dotted lines, the cord 61 will become taut and will open door 13 to an extent sufficient to permit access to box 12 of the exposed sheet of sensitized paper which slides from the frame through slot 55 therein. A sheet of sensitized paper thus finding access to box 12 drops to the lower part of the box and stands upright therein as shown at 62. It is particularly to be noted that the sheet will not slide from the frame until the pressure back 50 is relieved through the opening of the usual catch 63. When the pressure back is swung to its open position, as indicated in dotted lines, it completely covers the top of box 12 and shields the interior of the box from extraneous light while affording access of the exposed sheet thereto.

It is thought that the operation of the device will be perfectly clear to those skilled in the art from the foregoing description of the parts and their several functions but for convenience a summary will now be given of the manner in which the device is used in practice.

The negative and mask will be inserted in 95 the open printing frame when such frame occupies the position indicated in dotted lines. The device is particularly adapted for use in the printing of large quantities of 100 pictures from a single negative and it may be assumed therefore that the negative and mask are allowed to remain unchanged between successive printing operations. After the negative and mask are in place a sheet of 105 sensitized paper is inserted in the frame above them and the hinged back 50 of the frame is closed and secured by the customary latch 63. When the frame is in the dotted line position a spring contact 41 will be engaged with stationary switch terminal 110 44 to close the circuit including the ruby or safe light 29 for the convenience of the operator in manipulating the sensitized 115 sheet into place and in ascertaining that the negative is properly positioned with reference to the mask.

When the frame is swung counterclockwise toward its full line position the circuit to lamp 29 is broken and after somewhat more than 180° of oscillation the lug 40 on 120 the frame will contact shoulder 39 on spring 38 to limit the oscillatory movement of the frame and at approximately the same time to close the circuit which includes light 22. This light is now directed evenly upon the negative by means of reflector 21 and after the proper length of time the sensitized sheet 60 will receive an adequate exposure. Thereupon the operator presses downwardly 125 upon the outwardly projecting margin of 130

frame 25 to swing the frame in the direction indicated by the arrow. Immediately the light 22 is extinguished and as the frame approaches its dotted line position, bulb 29 is again illuminated and the tension of cord 61 results in opening door 13. As the frame reaches the indicated dotted line position, the operator releases the latch 63 and throws open the back 50 of the frame which 10 extends across the top of box 12. The relief of pressure on the sensitized sheet 60 allows such sheet to slide through slot 55 in the frame into the box 12 where it joins the previously exposed sheets which are piled 15 as at 62 in such box. The release of the sensitized sheet takes place under such circumstances that the frame is in readiness to receive a new sheet and consequently the entire operation may be repeated indefinitely 20 with great speed.

I claim:

1. In a device of the character described, the combination with a printing frame supported for oscillation about a substantially 25 horizontal axis, of an incandescent bulb arranged to illuminate a face of said frame in one position of oscillation thereof, and a switch controlling the illumination of said bulb and including a moving contact element disposed in the path of oscillation of said frame and adapted to be adjusted by the frame to switch closing position, said element including a stop member adapted to abut said frame to define said position 30 thereof.

2. In a device of the character described, the combination with a frame supported for oscillation and an incandescent bulb positioned to illuminate a face of said frame in 40 one position of oscillation thereof, of switch means automatically operable in accordance with the movement of said frame to control the incandescence of said bulb and adapted to render said bulb incandescent in said 45 frame position only, said means including a movable switch element disposed in the path of oscillation of a portion of said frame and a frame portion eccentrically formed for contacting said element in but 50 one position of said frame, said contact element being provided with a stop adapted to limit frame movement and to define said position.

3. In a device of the character described, 55 the combination with a cabinet provided with an opening in its face and with a source of illumination, of a printing frame provided with laterally extending trunnions journalled with respect to the sides of said 60 cabinet, said frame being so positioned as to be accessible through said opening at all times.

4. In a device of the character described, 65 the combination with a cabinet provided with an opening in its face and with a

source of illumination, of a printing frame provided with laterally extending trunnions journalled with respect to the sides of said cabinet, said frame being so positioned as to be accessible through said opening at 70 all times, together with a plurality of incandescent bulbs within said cabinet, independently controllable electric circuits for said bulbs including separate switches provided with movable contact elements disposed respectively in the paths of movement of portions of said frame and adapted in different positions of said frame to be closed thereby, one of said elements being provided with a stop adapted to limit the oscillation 75 of said frame about said trunnions in one direction.

5. In a device of the character described, the combination with a cabinet having a print exposing compartment and a compartment for exposed prints, of a frame mounted in said first mentioned compartment for oscillation therein and provided with a delivery slot and a back in releasable pressure relation to said frame, said slot being 80 adapted to deliver prints from the interior of said frame upon the release of the pressure of said back and said exposed print compartment being so located as to receive prints from said frame when said frame is 85 at an angle for the gravity delivery of a print through said slot.

6. In a device of the character described, the combination with a cabinet having a print exposing compartment and a compartment for exposed prints, of a frame mounted in said first mentioned compartment for oscillation therein and provided with a delivery slot and a back in releasable pressure relation to said frame, said slot being 90 adapted to deliver prints from the interior of said frame upon the release of the pressure of said back and said exposed print compartment being so located as to receive prints from said frame when said frame is 95 at an angle for the gravity delivery of a print through said slot, together with a door for said last mentioned compartment, and means for automatically controlling the movement of said door in accordance with 100 the movement of said frame to and from said last mentioned position.

7. In a device of the character described, the combination with a cabinet having print exposing and print storage compartments, 105 of a frame slotted at its end and supported for oscillation in the print exposing compartment, said frame being adapted in a first position thereof for the gravity discharge of a print into said storage compartment and a source of illumination adapted in a second position of said frame 110 to illuminate a face thereof and to expose a print contained therein.

8. In a device of the character described,

the combination with a cabinet having print exposing and print storage compartments, of a frame slotted at its end and supported for oscillation in the print exposing compartment, said frame being adapted in a first position thereof for the gravity discharge of a print into said storage compartment and a source of illumination adapted in a second position of said frame 10 to illuminate a face thereon and to expose a print contained therein, and means automatically operative in accordance with the movement of said frame to and from said first position for controlling communication 15 between said exposing and storage compartments.

9. In a device of the character described, the combination with a cabinet having print exposing and print storage compartments, 20 of a frame slotted at its end and supported for oscillation in the print exposing compartment, said frame being adapted in a first position thereto for the gravity discharge of a print into said storage compartment and a source of illumination 25 adapted in a second position of said frame to illuminate a face thereon and to expose a print contained therein, means automatically operative in accordance with the movement of said frame to and from said first 30 position for controlling communication between said exposing and storage compartments, and means automatically operative in accordance with the movement of said 35 frame to and from its second position for controlling the illumination of said print from said source.

10. In a device of the character described, the combination with a cabinet having an 40 opening in its front and a box positioned below said opening and provided with a normally closed downwardly yielding cover, of a printing frame supported for oscillation within said cabinet and adapted to project 45 therefrom through said opening in its horizontal positions, said frame being slotted in one of its ends whereby to be adapted for gravity delivery of prints into said box, together with a cord connected with 50 said cover and with the unslotted end of said frame and of such a length as to remain normally slack during the major portion of the movement of said frame and to be drawn taut during the final oscillation of 55 said frame away from its horizontal position, whereby to open said cover.

11. In a device of the character described, the combination with a cabinet having an 60 opening in its front and a box positioned below said opening and provided with a normally closed downwardly yielding cover, of a printing frame supported for oscillation within said cabinet and adapted to project 65 therefrom through said opening in its horizontal position, said frame being slotted

in one of its ends whereby to be adapted for gravity delivery of prints into said box, together with connections automatically operative in accordance with the movements of said frame for pressing downwardly the 70 door of said box as said frame approaches a position for print delivery thereto.

12. In a device of the character described, the combination with a cabinet having printing and storage compartments and a door 75 controlling communication between said compartments, of a printing frame supported for oscillation in said cabinet and connections between said frame and said door adapted to open said door as said frame oscillates 80 toward one position in said cabinet.

13. In a device of the character described, the combination with a cabinet having printing and storage compartments and a door controlling communication therethrough, of 85 a printing frame mounted in the exposing compartment of said cabinet, connections between said frame and said door for the opening of said door in one position of oscillation of said frame, and a back in releasable pressure relation to said frame, said frame being provided with a slot in the end nearest said storage compartment when said frame is in a position for the opening of said door. 90

14. In a device of the character described, the combination with a cabinet having printing and storage compartments and a door controlling communication therethrough, of 100 a printing frame mounted in the exposing compartment of said cabinet, connections between said frame and said door for the opening of said door in one position of oscillation of said frame, a back in releasable pressure relation to said frame, said frame being provided with a slot in the end nearest said storage compartment when said frame is in a position for the opening of said door, together with an incandescent 105 bulb positioned to illuminate a face of said frame when said frame occupies a second position of oscillation in which said connections are not operative to open said door, and a switch controlling the illumination 110 of said bulb and including a moving contact element disposed to be engaged by the portion of said frame when said frame reaches said second position.

15. In a device of the character described, the combination with a cabinet having an 120 opening in its face, of a box connected with said cabinet to comprise a compartment thereof and provided with a door immediately exterior of the opening in the face of said cabinet and controlling communication 125 between the interior of said cabinet and the interior of said box, an oscillatable printing frame provided with laterally projecting trunnions journalled with respect to the sides of said cabinet, said frame being 130

mounted to project through the opening in said cabinet when horizontal, said frame being provided with a slot in an end of said frame and adapted in an inclined position of said frame to deliver a print through said opening and into said box.

16. In a device of the character described, the combination with a cabinet having an opening in its face, of a box connected with said cabinet to comprise a compartment thereof and provided with a door immediately exterior of the opening in the face of said cabinet and controlling communication between the interior of said cabinet and the interior of said box, an oscillatable printing frame provided with laterally projecting trunnions journaled with respect to the sides of said cabinet, said frame being mounted to project through the opening in said cabinet when horizontal, said frame being provided with a slot in an end of said frame and adapted in an inclined position of said frame to deliver a print through said opening and into said box, means for yieldably maintaining the door of said box normally closed, and a normally slack tension member connecting said door with said frame and adapted to open said door as said frame oscillates toward an inclined position for the delivery of a print through said slot.

17. In a device of the character described, the combination with a cabinet having an opening in its face, of a box connected with said cabinet to comprise a compartment thereof and provided with a door immediately exterior of the opening in the face of said cabinet and controlling communication between the interior of said cabinet and the interior of said box, an oscillation printing frame provided with laterally projecting trunnions journaled with respect to the sides of said cabinet,

said frame being mounted to project through the opening in said cabinet when horizontal, said frame being provided with a slot in an end of said frame and adapted in an inclined position of said frame to deliver a print through said opening and into said box, means for yieldably maintaining the door of said box normally closed, and a normally slack tension member connecting said door with said frame and adapted to open said door as said frame oscillates toward an inclined position for the delivery of a print through said slot, together with a back for said frame in releasable pressure engagement therewith.

18. In a device of the character described, the combination with a printing frame supported for oscillation and provided with a slotted end whereby to be adapted in an inclined position of said frame for the discharge of a print therethrough, an incandescent bulb arranged for the illumination of a face of said frame in a second position thereof, electrical connections for said bulb including a switch having a moving contact, a pressure back for said frame in releasable pressure engagement therewith, said frame being provided at its slotted end with a portion adapted for engagement with the movable contact of said switch in a manner for the closing of said switch in the horizontal position of said frame, a compartment provided with an opening positioned to receive prints from the slotted end of said frame in the inclined position thereof, a door controlling communication with said compartment, and a normally slack connection between said door and the end of said frame opposite to the slotted end aforesaid, said connection being adapted to draw said door open as said frame approaches its inclined position.

ALBERT WIRTHWEIN.
